UNITED STATES PATENT OFFICE.

PETER SWANSON AND AXEL W. CARLSON, OF ELY, MINNESOTA.

AUXILIARY CAR STEP.

Application filed April 23, 1923. Serial No. 634,113.

To all whom it may concern:

Be it known that we, PETER SWANSON and AXEL W. CARLSON, citizens of the United States, residing at Ely, in the county of St. Louis and State of Minnesota, have invented certain new and useful Improvements in Auxiliary Car Steps, of which the following is a specification, reference being had therein to the accompanying drawing.

- 10 This invention relates to improvements in auxiliary steps for railway car platforms and has for its principal object to provide such a step which is more practical and conveniently operated than heretofore known.
- 15 Another object of the invention is to provide automatic locking means whereby the step will become locked automatically when either raised or fully extended.

Other objects and advantages of the invention will appear in the further description thereof.

Referring to the accompanying drawings forming part of this application in which like reference characters indicate like parts:

25 Figure 1 is a perspective view of the broken away lower portion of the vestibule of a railway car showing the under back view of the steps into the vestibule with the auxiliary step and trap door of the vestibule 30 open.

Figure 2 is a perspective view of the operating lever showing the guard for the upper end thereof;

35 Figure 3 is a view similar to Figure 1 of a modified form of the invention;

Figure 4 is a sectional view through the automatic locking means.

1 and 2 represent the opposite side walls of the ordinary steps into the vestibule of a 40 railway passenger car, to the lower outer corners of which is pivotally suspended as by suitable links 3 the auxiliary step 4. The links 3 are pivotally attached to the rear-most corners of the step as at 5 so that the 45 step when lowered into receptive position for a pedestrian will occur in proper sequence with the stationary vestibule steps, and when folded upwardly and backwardly will occur in close proximity to the under side of the 50 lowermost stationary step.

Spaced arms 6 are rigidly fixed to the under side of the step 4, extend rearwardly thereof, and are bent upwardly as at 7, where they are pivotally connected as at 8, 55 to the depending arms 9, rigidly fixed to the transverse rotatable shaft 10, which is suit-

ably journaled as at 11 upon the inner faces of the rearmost portions of the side walls 1 and 2.

Securely fixed to the shaft 10 in any desired manner is the upstanding lever 12, the upper end of which is substantially clover-shaped, and having the like clover-shaped opening 13 therein, the purpose of which will become apparent later. A vertical lever 14 is journaled as at 15 to the wall of the vestibule, extends upwardly through the floor or platform 16, through the journal bearing 17 and to the upper end of which is secured the lever 18 which is similar in 60 shape to the lever 12. The lower end of the lever 14 is bent inwardly and made to pass through the opening 19 in the wall 1 and also through the opening 13 in the lever 12. The operating lever 20 is pivotally secured 65 to the floor of the vestibule in any desired manner as at 21, and extends through the clover-shaped opening 22 in the free end of the lever 18. The upper end of the operating lever is provided with the diagonally extending extension 23, which is made to reciprocate, when the lever is operated, under the arcuately shaped guard 24, fixed to the wall of the vestibule. Thus it will be impossible for the clothing of a passenger of 70 the car to become caught on the lever.

It will be understood that the length of throw of the operating lever is regulated by the distance it is spaced from the shaft 14, and also by the length of the bight of the 75 lever, either of which may be varied to suit the requirements.

Thus when the lever 20 is in the position shown, the step will be in extended position, but when the lever 20 is reversed it will bring the auxiliary step up against the bottom of the last fixed step and in which position it will be at all times when the car is moving.

Because of the fact that the links 3 are 80 attached to the rearmost corners of the auxiliary step, when a weight is applied thereon the tendency of the step will be to swing under the car, which it would do were it not for the specific clover-shaped openings 13 and 22 in the levers 12 and 18 respectively; the lower corners of the openings binding or pinching the levers passing therethrough. However when the lever 20 is moved in either direction it will pass the corners of 85 the opening in the lever 18 before they will have a chance to bind; thus the operating

lever is automatically locked in either extreme position, except when manually manipulated.

The shaft 14 is provided with an annular 5 enlargement 25 which fits within an opening in the bearing or bracket 15 when the latter is applied as illustrated in Figure 1 and forms admirable means for maintaining the shaft 14 against vertical movement 10 which is obviously necessary to the successful operation of the device.

In the modified form illustrated in Figure 3, the shaft 10 extends through the side wall 1 and the lever 12 is fixed to the extreme end thereof. The lower forked end 15 of the operating lever 25 is made to overlap the lever 12 and the holes in lever 25 register with the opening 13, when the pin 27 is inserted through the thus registering holes 20 which forms the pivotal connection between the operating lever and the locking lever 12. The pin is provided with a shoulder 28 and the outer end of the pin is screw threaded and has the nut 29 applied thereto to hold 25 the pivotal connection secure. Before the pin 27 is applied a sleeve 30 is slid thereabouts so that the pin will be saved of excessive wear through the operation of the levers.

30 The trap door 31 of the car may be operated and held in closed position by means of the door bolt 32 securely bolted to the floor of the car; and the upstanding lever 33 is provided for the operation of the door bolt when it is desired to open the trap door, the upper end thereof being bent over 35 to form a convenient handle for this purpose. Securely fixed to the operating lever 33, and in the normal path of the operating lever 25, is the wire bracket 34, it being so positioned for the purpose of releasing the door catch and allowing the trap door to spring open when the operating lever is pushed forwardly in the act of extending the auxiliary car step; the lever 25 striking the bracket 34 and thus turning the lever 33 40 and releasing the door.

45 The outer fork of the bifurcated handle 25 is provided with an offset extension 25 the same being in the form of a handle so that the auxiliary step and trap door may be conveniently operated from the exterior of the car.

50 I have also shown a spiral spring, 36, one end of which is secured to a strap 37 fixed to the bottom of the auxiliary step and the

other end to a strap fixed to the bottom of one of the fixed stationary steps, the purpose of the spring being to aid in the operation of the step when being returned to inoperative position, and it is obvious that other modifications within the scope of the appended claims may be resorted to without departing from the spirit of the invention. 60

Furthermore applicant wishes it to be understood that he is not limited, with respect to his novel lever locking means, to an auxiliary car step for railway cars, as the same may be readily applied to opening the doors of street cars, automobile busses, or the like. 65 70

Having thus described our invention, what we claim and desire to secure by Letters Patent is:

1. The combination with a car platform auxiliary step controlled by a horizontally 75 disposed shaft below the platform, of a vertically disposed shaft extending through the platform, combined cooperating and locking means intermediate of the two shafts, and combined operating and locking means co-operatively connected with the upper end of the vertical shaft.

2. A locking device for levers consisting of a pivotally mounted member, a clover-shaped opening in the free end of the member through which the lever to be locked passes whereby the lever will be locked in either extreme position, substantially as described. 85

3. A locking device for levers consisting 90 of a pivotally mounted member, a clover-shaped opening in the free end of the member through which the lever to be locked passes whereby either corner of the opening will prevent the lever from operating 95 when pivotal movement is imparted to the member.

4. An automatic lever lock consisting of an operating lever and a locking lever, a clover shaped opening in the locking lever 100 through which the operating lever is operatively connected, and means whereby the operating lever will be locked in either extreme position, substantially as described.

105 In testimony whereof we hereunto affix our signatures in the presence of two witnesses.

PETER SWANSON.
AXEL W. CARLSON.
